UNITED STATES PATENT OFFICE.

FRANK W. GENT, OF WELLSVILLE, NEW YORK.

SOFA-BED.

1,233,218.

Specification of Letters Patent. Patented July 10, 1917.

Application filed July 27, 1914. Serial No. 853,257.

To all whom it may concern:

Be it known that I, FRANK W. GENT, a citizen of the United States, residing at Wellsville, in the county of Allegany and State of New York, have invented certain new and useful Improvements in Sofa-Beds, of which the following, taken in connection with the accompanying drawings, is a specification.

10 The invention relates to combination sofa and bed construction by means of which a sofa can be quickly and easily changed into a bed or a bed into a sofa; and the improvements consist in providing a folding bed 15 with hinged arms for the sofa ends and an attachment which supports the hinged sofa arms in different positions in relation to the sofa end, and the construction of said attachment is such that when the arms are in 20 the horizontal or semi-lowered position they are so strongly supported that they may form seats or head supports for the bed or sofa end; and the invention consists in 25 the novel features and combinations herein-after set forth and claimed.

In the drawings, Figure 1 is a perspective view of the sofa with the folding bed in the open position and the sofa arms turned down into the horizontal or seat position, 30 showing the convenience of the construction.

Fig. 2 is a perspective view of the outer side of the sofa bed end without the upholstering cover, showing the frame work 35 and hinge and support construction for the sofa arm; and Fig. 3 is a front elevation of the sofa bed end, showing the arm in the lowered or horizontal position, the semi-lowered being shown in dotted outline.

40 Fig. 4 is a perspective view of the lower portion of the supporting attachment for the sofa arm; Fig. 5 is a perspective view of the lower end of the link for attaching to the sofa arm; Fig. 6 is an elevation of 45 the parts with the link pin in section at the point where it passes the latch on the lower supporting plate; and Fig. 7 is an elevation of the supporting attachment with the link pin in the semi-lowered position 50 within the supporting notch on the plate.

Fig. 8 is a plan view of the uncovered sofa end frame, showing the beveled joint between the back and sofa arm.

Like numerals of reference refer to corresponding parts in the several views,

The numeral 10 designates the sofa which has the ends 11, back 12, and arms 13 which are hinged at 14 to the sofa end 11.

The frame of the sofa end 11 is connected to the back 12 and the frame for the arms 13 is separated from the back portion of the end 11 by the beveled joint 15 so that the arm 13 shuts against the beveled portion of the end 11 and a spring catch 16 holds the arm firmly in the vertical position.

The frames for the end 11 and arm 13 are composed of two vertical standards made from heavy frame pieces which are connected by strong cross bars and are severed about midway of their length by a V-shaped opening 17 which opens outwardly. The hinges 14 are placed at the bottom of the V or in line with the inner edge of said standards so that a limited hinge or turning movement is permitted the arms 13, said

turning movement being limited by the size of the V-shaped opening 17, preferably permitting the arm 13 to turn to the horizontal position, in which position the opposite walls of the V-shaped opening 17 rest upon one another.

A double link attachment is provided between the arm 13 and the end 11 on each of said standards to hold the arm 13 firmly in line and at the same time arrange for supporting it in an exactly horizontal position or semi-lowered position as for a head support, which attachment is

constructed as follows: A lower holding plate 18 is attached by suitable screws through screw-holes 19 in the lower end and is off-set above said points of attachment so as to permit a link piece 20 passing in between the plate 18 and the frame work of the sofa end 11.

The plate 18 has a long curved or bowed slot 21 which receives therethrough the headed pin or wrist 22 on the link 20, which pin plays upward and downward within the slot 21 as the arm 13 is raised and lowered allowing its free end movement. The slot 21 is of exactly the correct length to permit the arm 13 being raised to the vertical position, as shown in Fig. 2, or to the horizontal position, as shown in Fig. 3, in which

horizontal position the pin 22 of the link 20 rests in the lower end of the slot 21, as shown in dotted outline in Fig. 7.

A notch 23 is provided midway of the length of the side wall of the slot into which

100 the pin 22 of the link 20 rests in the lower end of the slot 21, as shown in dotted outline in Fig. 7.

105 A notch 23 is provided midway of the length of the side wall of the slot into which

110 the pin 22 of the link 20 rests in the lower end of the slot 21, as shown in dotted outline in Fig. 7.

the pin 22 passes as the arm is raised. In order that the pin 22 may pass freely to the lower end of the slot 21 in turning the arm 13 to the horizontal position and not enter notch 23, a latch piece 25 is provided which is pivotally attached to the plate 18 so that the end 26 of the latch piece 25 extends into the slot 21 and closes the notch 23 when in its normal lowered position. A sidewise enlargement 24 is provided in the opposite wall of the slot 21 from the point 26 of the latch 25 when in the lowered position to permit the free passage of the pin 22 to the lower end of the slot 21.

As the pin 22 passes up from the lower end of the slot it engages the point 26 of the latch 25, as shown in dotted line in Fig. 7, raising the latch 25 and permitting the pin 22 to pass into the notch 23. In order that the latch piece 25 may not get out of position a long notch 27 is provided in the lower side of the latch 25 and a pin 28 is provided on the plate 18 which engages in the notch 27 thereby controlling the pivotal movement of the latch piece 25 yet permitting the free ingress and egress of the pin 22 from the notch 23 when said pin 22 is raised from the lower position, but guarding the notch 23 as said pin 22 passes downward from the upper portion of the slot 21. The upper end of the link 20 is pivotally attached to a bracket piece 29 which is attached to the frame work of the sofa arm 13.

It is now apparent that the sofa bed arm 35 may be raised to the vertical position shown in Fig. 2, in which position the link 20 will draw the wrist pin 22 to the upper end of the slot 21. When it is desired to turn the arm 13 to the horizontal or seat 40 position it is simply pushed outward and the pin 22 passes to the lower end of the slot 21 where it is firmly supported. When, however, it is desired to hold the arm 13 in an inclined or semi-lowered position as 45 shown in dotted line in Fig. 3 for a head support for the sofa or to assist in supporting the pillows for the sofa bed, the arm 13 is raised from the lower portion of the slot 21 thereby engaging the point 26 of the latch 25 with the pin 22 and raising said latch 25 and permitting said pin 22 to pass into the notch 23, thereby firmly supporting said arm 13 in the semi-lowered position. It is obvious also that a plurality 55 of notches similar to notch 23 with latches 25 may be provided in the side wall of the slot 21 to provide for graduated adjustments of the arm 13 without departing from my invention.

60 The two links 20 with their supporting plates 18 and 29 form an exceedingly strong and durable support for the sofa bed arm at the exact position desired, and when it is desired to raise the arm 13 to the vertical 65 position it is simply lifted into place and

held by the spring catch 16, the latch piece 25 passing out of the way of the pin 22 as it is raised upward.

It is also obvious that the sofa bed seat 30 may be hinged to the frame so that it 70 can be turned forward, as shown in Fig. 1, and a folding spring bed 32 provided within the seat 30 having suitable hinged leg supports and hinged attachment to the sofa frame and that when spread forth in the 75 position shown in Fig. 1 forms a strong and convenient bed with the sofa arms 13 turned down out of the way to serve as convenient seats or for other purposes.

I claim as new:

1. In combination with a sofa frame, an 80 end hinged thereto, a link pivoted to said end, slotted means on the frame, a projection on said link movable in said slot, said slot having a lateral extension, and a 85 gravity latch controlling the entrance to said extension.

2. In combination with a sofa frame and a hinged end therefor, a link pivoted to 90 said end and having a projection, means on the frame slotted to receive said projection, the slot being laterally extended to hold the link inclined in one position of the link, and means operable by the projection for controlling the admission of 95 the projection into the lateral slot extension.

3. A sofa bed end consisting of a sofa 100 end frame, an arm hinged on said sofa end frame to turn outwardly, a support for said arm comprising a link pivotally attached to its upper end to said arm, a wrist pin 105 on the lower end of said link, a plate attached to said end frame below said arm, said plate having a slot therein engaged by said wrist pin, said slot bowed to allow the free action of said link in raising and lowering said arm, said slot having a notch in the side wall thereof, a latch on said plate to normally close the mouth of said 110 notch, said latch adapted to be raised by said wrist pin and link.

4. A sofa bed end comprising an end frame, an arm hinged to said end frame, an attachment for supporting said arm in a 115 lowered position comprising a slotted plate having a notch in the side wall of the slot, a latch to guard said notch and extending into said slot, the wall of said slot having a sidewise enlargement opposite said latch, 120 said slotted plate attached to said end frame, and a link pivotally attached to said arm and engaging in said slot to enter said notch and support said hinged arm in the lowered position.

5. A sofa bed end comprising a frame, an arm hinged on said frame and having a rearwardly oblique joint between said arm and the rear portion of said frame, a spring catch on said rear portion to hold said arm 130

in the raised position, a pair of attachments 5 for supporting said arm in the horizontal position each comprising a link pivotally attached to the arm, a slotted plate attached to the end frame beneath said pivotally attached link and engaged thereby within the slot in said plate, said slot formed to permit the movement of said arm from the raised to the lowered position, said plate 10 having a notch in the side wall of said slot to be engaged by said link, a latch pivotally attached to said plate to close the opening into said notch and extending into said slot, said plate having a sidewise enlargement 15 in the wall of said slot opposite said latch, and a notch in said latch and a pin on said plate to control the position of said latch.

6. In combination with a sofa frame, and 20 a hinged end thereon, a supporting element connected to the end, means engaging the element having a part to hold the end horizontal and a second part to hold the end at an incline, and means normally guarding 25 said second part from engagement by the

supporting element but adapted to be displaced from guarding position by a certain predetermined movement of said supporting element to allow such engagement whereby the said sofa end is held in inclined position. 30

7. In combination with a sofa frame, and a hinged end thereon, a supporting element connected to the end, means engaging the element having a part to hold the end horizontal and a second part to hold the end at an incline, and swingable gravity responsive means normally guarding said second part from engagement by the supporting element but adapted to be displaced from guarding position by a certain predetermined movement of said supporting element to allow such engagement whereby the 35 40 45 said sofa end is held in inclined position.

In testimony whereof I have affixed my signature in the presence of two witnesses.

FRANK W. GENT.
